UNITED STATES PATENT OFFICE

2,487,878

STATIONARY CONNECTOR FOR TERMINI OF
ANGULARLY DISPOSED CONVEYERS

Oscar E. Kantenwein, Chicago, Ill.

Application July 29, 1947, Serial No. 764,512

3 Claims. (Cl. 193—35)

1

My invention relates to stationary table interconnecting devices between angularly disposed conveyors, to replace the customary turntable structure used for the same purposes.

An important object of my invention is to provide a stationary table interconnecting device that may be used to connect from two or more angularly disposed conveyors, either of a horizontal type or a gravity type conveyor.

A further object of my invention is to provide a stationary table interconnecting device that, by means of a number of rows of ball bearings, the tops of which extend slightly above the floor of the said stationary table, dollies or boxes may be easily moved from the connecting conveyor, pivoted on the stationary interconnecting device, and moved onto a second angularly disposed conveyor.

A further object of my invention is to provide a stationary interconnecting device that may be set into the cement flooring at the same level as the horizontal conveyor track embedded in the floor, to which it is connected, or it may be set at any higher level that is convenient for the operator, and may be used with gravity type conveyors.

A still further object of my invention is to provide, in a stationary table interconnecting device, a curbing means high enough to act as a guide to the edge of the dolly as it is being swung from one conveyor track to another angularly disposed conveyor track.

A still further object of my invention is to provide a dolly, into the four corners of which are set ball bearings, to provide a frictionless turning means against the aforementioned curbing, as the dolly is shifted in its directional path from one conveyor track to another.

A still further object of my invention is to provide, in a stationary table interconnecting device, a slipproof floor, the surface of which is suitably roughened to provide a safe footing and traction for the operator.

Another object of my invention is to provide a stationary table interconnecting unit, consisting of substantially two right angular sectors having extending upright walls defining dihedral angles, the said walls and the said angles cooperating in deflecting the path of a load traversing the said conveyors.

Other objects and advantages inherent in my invention will become readily apparent from the ensuing description and the accompanying drawings, in which like parts are designated by like numbers, and in which:

2

Fig. 1 represents a perspective view of my invention showing it connected to two gravity conveyors and showing an operator in the act of turning a dolly from one conveyor to another.

Fig. 2 is a cross-sectional view taken substantially on lines 2—2 of Fig. 1.

Fig. 3 is a perspective view of my invention showing it set into a cement floor and connected to two angularly disposed horizontal conveyors embedded in the floor.

Fig. 4 is a top view of my invention showing it set into a cement floor and connecting three angularly disposed horizontal conveyors embedded in the floor.

Fig. 5 is a cross-sectional view of a portion of my invention taken substantially on lines 5—5 of Fig. 4.

Fig. 6 is a top view of my invention showing it set into the cement floor and connecting four angularly disposed horizontal conveyors embedded in the floor.

Fig. 7 is a perspective view of a dolly with parts broken away to show its operation and position on my stationary table interconnecting device.

The customary manner, at present employed, for deflecting the path of a load transferred over angularly disposed conveyors is to use an expensive turntable device or unit requiring expensive motivating equipment in association therewith and the use of electrical or other source of power as a constant expense in the operation of the said turntable.

Incidental with turntable devices and their associated mechanism, they are subjected to wear and tear to a greater extent, requiring maintenance, upkeep, and further expenses in their maintenance for efficient operation. My stationary table is more efficient and a decided advantage over the present systems.

My invention generally designated 8 consists of two quadrants or sectors 9, which are connected by two oppositely disposed dihedral side formations 21 and 22.

In my invention generally designated 8, shown in Fig. 1, the dihedral shaped side portions 22 are slightly bent at 23 to join the arcuate portions 9. A circular bottom 10 and a flooring 11 having suitable shape to mate with the said sectors 9 to complete the structure and provide housing for a number of rows of ball bearings 14. The ball bearings 14 may revolve on a bed of small ball bearings 16 in a hemispherical housing 15, so arranged that a small portion of the ball bearings 14 extend through openings 13 in

the floor 11, above the level of the projections 12 on the said floor 11.

The two angularly disposed gravity conveyors 24 are attached to my invention, on one side to a flange 25 on the arcuate side 9, and on the other side by a plate 26 attached to the side 21.

My invention, designated 8, as shown in Fig. 1, is provided with a number of legs 17, the height being sufficient to allow an operator 32, as shown in dotted lines, to easily manipulate and shift the path of dolly 28 from one to another of the two angularly disposed gravity conveyors 24. The dolly 28, in this instance, is shown with side racks 29 and carrying a load 30, and riding on the rollers 27 of the gravity conveyor 24 in the direction of the arrows 44 in Fig. 1.

A suitable dolly, as shown in Fig. 7, may be constructed of heavy planks 38, held together by an iron band 39 and having proportions suitable to enable it to shift within the curbing 19 around the wall of the stationary table interconnecting device, its width being determined by the width of the conveyors 24. The dolly 28 may also be provided with four ball bearings 31, set one in each of the four corners of the said dolly in hemispherical housings 41 and rotating upon small ball bearings 42.

A number of recessed openings 40 around the edge of the dolly 28 provide support for the rack posts 43, or for the side and end plates to make up the enclosure 29. As the dolly 28 reaches a position on the surface of the table interconnecting 30 device 8, as shown in full lines in Fig. 1, the ball bearing 31 in the front corner of the dolly 28 will be deflected by the deflector curb 23 of the sides 22 and begin to turn the dolly on the ball bearings 14 of the connector 8.

The operator 32 grasps the dolly 28 without checking its movement and pivots it upon the apex 33 of the dihedral angle which aids in the initiation of the shifting movement, turning it in the direction of the arrows 45 until it is angularly disposed in alignment with the second gravity conveyor 24 and moving in the direction of the arrow 46.

Fig. 3 illustrates a slight modification of my invention, generally designated 34, which differs from the first illustrated type only in that it is set into the cement floor 18 so that the top of its curbing 19 is flush with the top of the cement floor 18, and its floor 11 is flush with the floors of the two angularly disposed conveyors 35 to which it is connected.

The stationary table interconnecting device 34 is attached to the two angularly disposed horizontal conveyors 35 in the same manner as that previously described for the stationary table interconnecting device 8 and the gravity conveyors 24, except that there are no legs 17 provided in this instance. The tops of the ball bearings 14 are the same distance above the floor 11 as the tops of the rollers 37 are above the tracks of the conveyors 35, so that a dolly 28, as shown in Fig. 3 in solid lines, may be pushed easily from the conveyor 35 onto the stationary interconnecting table 34 shifted to assume a path in the direction of the arrows 45 and off the conveyor connector in the direction of the arrows 46 on the second of the two angularly disposed conveyors 35.

The dolly 28, at all times, is tangentially in contact with the rollers 37 or with the balls 14, the exposed surfaces of the balls 14 being spaced sufficiently apart and extending above the projections 12, thus affording firm footage and traction

to the soles of the shoes of an operator during the dolly manipulating operation.

Fig. 4 further illustrates a further modification of my invention, designated 36, which is similar to the modification, designated 34, except that it connects three angularly disposed conveyors 35 instead of two, so that a dolly 28 may be pushed onto the conveyor connector 36 from either of two directions and straight across, or maybe pivoted angularly to a third direction, as shown by full and dotted lines in Fig. 4.

A fourth modification of my invention, as illustrated in Fig. 6, and is generally designated 37'. It is similar to modification designated 36 except that it connects four angularly disposed conveyors 35 instead of three, so that dolly loads 28 may be pushed onto the conveyor connectors 37' from any one of four directions as represented, in this instance, by crossing aisles between the walls 47.

The illustrations 1, 3, 4 and 6 show the simple and compact form of my conveyor stationary interconnecting table which can be installed in the restricted areas illustrated, at the same time functioning as a most efficient conveyor connector.

It will be noted that the sides 21 are of a somewhat heavier construction than the sides 22 or the sides 9, due to the fact that the apex 33 acts as a pivoting point for the dolly 28 as it is turned from one angularly disposed conveyor to another.

The dolly 28 in Fig. 6 may be manipulated so that it travels in a straight path from one conveyor 35 to another conveyor 35 in co-extensive alignment therewith, or it may be deflected from one conveyor 35 to any of the angularly positioned conveyors 35.

Since many changes could be made in this construction without departure from the scope of the following claims, it is intended that all matter contained in the accompanying drawings, or in the foregoing description, shall be interpreted as illustrative rather than in a limiting sense.

Having thus described and disclosed my invention, what I claim as new, and desire to secure by Letters Patent is:

1. A conveyor mechanism comprising, at least two angularly disposed conveyors, and a stationary conveyor table interconnecting the said conveyors, the said table being provided with universal bearing means spaced at predetermined distances on the upper surface thereof, the spaces intermediate the said universal bearing means being roughened to afford traction to the shoe soles of an operator.

2. A conveyor mechanism comprising, at least two angularly disposed conveyors, and a stationary conveyor table interconnecting the said conveyors, the said table being provided with universal bearing means spaced at predetermined distances on the upper surface thereof, the said table composed of two sector sections having perimetraly thereabout a projecting guide wall broken at the juncture to the said angularly disposed conveyors.

3. A conveyor mechanism comprising, at least two angularly disposed conveyors, and a stationary conveyor table interconnecting the said conveyors, the said table being provided with universal bearing means spaced at predetermined distances on the upper surface thereof, the spaces intermediate the said universal bearing means being roughened to afford traction to the shoe soles of an operator, the said table composed of

2,487,878

5

two sector sections having perimetrical there-
about a projecting guide wall broken at the junc-
ture to the said angularly disposed conveyors.

OSCAR E. KANTENWEIN.
